CLAIM

The ornamental design for iron golf club head, as shown and described.

DESCRIPTION

FIG. 1 is a perspective back view of my new design for an iron golf club head;

FIG. 2 is a back view thereof;

FIG. 3 is a toe view thereof;

FIG. 4 is a heel sole view thereof;

FIG. 5 is a top view thereof;

FIG. 6 is a front view thereof; and,

FIG. 7 is a bottom sole view thereof.

The broken lines in the figures are used to illustrate the unclaimed portions of the invention and form no part of the claimed design.
